UNITED STATES PATENT OFFICE.

WALTER C. LINDEMANN AND KEY D. CAMP, OF MILWAUKEE, WISCONSIN, ASSIGNEES
TO A. J. LINDEMANN & HOVERSON CO., OF MILWAUKEE, WISCONSIN.

ELECTRIC WELDING-MACHINE.

1,155,497.

Specification of Letters Patent.

Patented Oct. 5, 1915.

Application filed February 18, 1913. Serial No. 749,191.

To all whom it may concern:

Be it known that we, WALTER C. LINDEMANN and KEY D. CAMP, both citizens of the United States, and residents of Milwaukee, in the county of Milwaukee and State of Wisconsin, have invented certain new and useful Improvements in Electric Welding-Machines; and we do hereby declare that the following is a full, clear, and exact 10 description thereof.

Our invention consists in what is herein particularly set forth with reference to the accompanying drawings and pointed out in the claims of this specification, its object being to provide electric spot-welding machines, having greater durability, simpler operation, increased efficiency and requiring less adjustment than those of ordinary construction, each of our improved machines 15 being so constructed as to be operated by power and usable for electric spot-welding of materials that have heretofore been so welded only by manually operated machines; an especial feature of our invention being 20 a cam-actuated reciprocal crosshead and the cam so contoured as to permit of a dwell of the crosshead for a time at the end of its stroke in each direction, but especially at the end of its downstroke, where said dwell 25 is sufficiently long as to permit of the make and break of an electric welding-circuit, by especially devised means, prior to the time the aforesaid crosshead starts upon its upward travel, whereby ample provision is had 30 for the completion of a weld of material that has been previously gripped between two electrodes of said circuit.

Figure 1 of the drawings represents a side elevation of one of our improved electric 40 spot-welding machines partly in section, the section being indicated by line 1—1 in the next described illustration; Fig. 2, a transverse sectional view of a fragment of the machine indicated by line 2—2 in Figs. 45 1 and 3; Fig. 3, a horizontal section of the same fragment of the machine indicated by line 3—3 in Figs. 1 and 2; Fig. 4, a transverse sectional view of another detail of the machine indicated by line 4—4 in Fig. 1, and 50 Fig. 5, a diagram of the electric-welding circuit.

Referring by numerals to the drawings, 6 indicates a stand upon which the base of a forwardly projecting upper arm 7 is suitably secured, and likewise secured in connec-

tion with said base is a lower forwardly projecting arm 8, the two arms being parallel and the upper one fashioned at its forward end to provide an angular clearance space and vertical cheeks 9. The arm 7 is 60 provided with bearings for a shaft 10 having a drive-pulley 11 and a start-and-stop collar 12 rigid therewith, a spring-and-treadle controlled latch-rod 13 engageable with the collar 12 being shown guided in 65 a bracket 14 of said arm. The detail of mechanism for controlling start and stop of the aforesaid shaft constitutes no part of our present invention, and any suitable means may be employed for the same purpose, it being understood that a driving-belt operates the pulley, and that said pulley runs idle when said shaft is not in action. 70

Keyed on the forward end of the shaft 10 is 75 a circular cam 15 within an angular frame 16 guided vertically in another angular frame 17 for which vertical guides 18 are provided, these guides being held in detachable connection with the cheeks 9 of the arm 7 by screws. The frames constitute a crosshead 80 and, as a matter of detail, the inner frame is provided with tongues engaging grooves in the outer frame and detachably held in place by face-plates 16' fastened by screws to said outer frame. 85

The inner frame of the crosshead is supported on compression springs 19, and opposed by an adjusting turret screw 21 depending from the outer frame of said crosshead. Attached to the crosshead is a yielding electric conductor 22 forming part of a secondary circuit of a transformer provided, with the machine. The conductor is shown as being composed of laminated copper strips, and clamped on its forward free end 90 under said crosshead, central of the same, is the shank 23 of a separable holder 24 for an electrode 25 opposing another electrode 26 clamped between the forward end of the arm 8 and a block 27 bolted thereto, the opposing faces of said arm and block being recessed to engage the interposed electrode. 95

Fast on the shaft 10 is an insulator-ring 28, and fitted tight on the ring is a contact-sleeve 29 having a lateral lug 30. In constant touch with the sleeve is a brush 31 for which a holder 32 is supported by an insulating plate 33 attached to a block 34, the block being insulated on the bracket 14 aforesaid. Pivoted in a longitudinal groove 110

of the block is a spring-controlled rocker 35 in the path of the lug 30 of the contact sleeve 29, said brush and rocker being terminals of the primary circuit of a transformer, which transformer is indicated at 5 36 in the diagram Fig. 5. The electrodes 25 and 26 are included in the secondary circuit of the transformer by any suitable electric practice, this disposition of said electrodes being illustrated in said diagram 10 Fig. 5.

The secondary circuit of the transformer is the welding-circuit of our machine, and in practice the material to be welded is laid 15 in on the electrode 26, after which the shaft 10 is released by a depression of the treadle 37, whereupon the cam 15 is rotated to depress the crosshead and the electrode 25, the normal position of the lug 30 of the contact sleeve 28 being such, as shown in Fig. 1, that it does not come into touch with the rocker terminal 35 to close said welding-circuit, as shown in Fig. 4, until subsequent to a gripping of said work between said electrodes. 20 The springs 19 are employed between the frames 16, 17 of the crosshead so that materials of variable thickness may be interposed between the electrodes without changing the adjustment of said crosshead, but said 25 springs have no bearing on the time interval 30 allowed for a welding operation, this being taken care of entirely by the timing of the cam 15. The action of the cam 15 takes place upon the inner frame 16 of the crosshead moving the entire crosshead (together 35 with the conductor 22) as though it were one piece until the material to be welded is gripped between the electrodes whereupon, due to the cam action, the crosshead re- 40 mains stationary for a definite predetermined interval of time, then starts its travel back to its original position. The springs 45 19 acting between inner frame 16 and outer frame 17 compensate for variations in thickness of the material to be welded and thus greater range to the setting of the electrodes and the adjustment of the crosshead is afforded. Subsequent to the gripping of 50 the material between the electrodes and 55 while the crosshead is at rest, the lug 30 extending from the sleeve 29, in revolution with the shaft 10, makes contact with the rocker 35 that yields against the spring 37 in opposition thereto. The transformer circuits are now closed and a welding of said 60 material between said electrodes takes place during the time the contact lug 30 is in rotary opposition to the rocker 35. At the instant the lug passes the rocker, the electric 65 circuits are broken with a sharp snap, due to spring action on said rocker causing the same to return to normal position, the independent reverse movement of said rocker being sufficient to break any electric-arc that 65 may take place between it and said lug.

The arc-breaking movement of the rocker takes place before the crosshead is lifted by the cam 15 to effect a release of the grip of the welding electrodes upon the interposed material, and the operation of the machine is recurrent as long as the aforesaid treadle is held down.

It will be understood from the foregoing that the circuit make and break mechanism, complete in itself, consists of the contact sleeve 29 having the lug 30, the brush 31 and brush-holder 32 on one side of the circuit, while on the other side of said circuit the spring-controlled rocker 35 is pivoted to permit the necessary amount of 70 movement at its contact-end, the pivoting being within the groove of the block 34 with the pivot so disposed as to provide for the necessary movement of the contact-end or arm of said rocker that extends outward 75 from said groove. The rocker shown is somewhat T-shaped and the block-groove has the bottom thereof beveled in opposite directions to permit of the desired pivotal play of said rocker, but the details of construction of the circuit make and break mechanism may be varied indefinitely from what has been specifically disclosed as an application in an electric circuit of a pair of 80 make and break contact devices one of which is movable past the other transversely thereto, and of which contact devices one at least 85 thereof is yielding to the other and automatically returnable to normal position on the instant of their clearance. The contact 90 devices aforesaid may be so constructed as to provide for renewal of their wearing surfaces.

We claim:

1. In an electric-welding machine, the combination of a driven shaft, a cam therewith, a sliding frame for which stationary guides are provided, another sliding frame guided in the one aforesaid and engaged by the cam, spring-resistance arranged between the two frames to oppose independent movement of the inner one for a time in one direction, a welding-circuit electrode movable with the crosshead formed by said frames, an opposing electrode in the same circuit, and means with the shaft for effecting an automatic make and break of said circuit during the interval of time the material to be welded is gripped between said electrodes and during which interval of time said inner frame may have independent yield to said cam against said spring-resistance.

2. In an electric-welding machine, the combination of a driven shaft, a cam therewith, a sliding frame for which stationary guides are provided, another sliding frame guided in the one aforesaid and engaged by the cam, spring-resistance arranged between the two frames to oppose independent move-

- ment of the inner one for a time in one direction, means controlling adjustment of the inner frame opposite said spring resistance, a welding-circuit electrode movable with the crosshead formed by said frames, an opposing electrode in the same circuit, and means with the shaft for effecting an automatic make and break of said circuit during the interval of time the material to be welded is gripped between said electrodes and during 10 which interval of time said inner frame may have independent yield to said cam against said spring-resistance.
3. In an electric-welding machine, the combination of a driven shaft, a cam there- 15 with, a sliding frame for which stationary guides are provided, another sliding frame guided in the one aforesaid and engaged by the same, spring-resistance arranged be- tween the two frames to oppose independent 20 movement of the inner one for a time in one direction, a turret-screw depending from the outer frame against the inner one opposite said spring resistance, a welding-circuit elec- trode movable with the crosshead formed 25 by said frames, an opposing electrode in the same circuit, and means with the shaft for effecting an automatic make and break of said circuit during the interval of time the material to be welded is gripped between 30 said electrodes and during which interval of time said inner frame may have independent yield to said cam against said spring-re- sistance.

In testimony that we claim the foregoing 35 we have hereunto set our hands at Milwaukee in the county of Milwaukee and State of Wisconsin in the presence of two wit- nesses.

WALTER C. LINDEMANN.
